(57) **CLAIM**

The ornamental design for a shaft coupling, as shown and described.

DESCRIPTION

FIG. 1 is an upper front perspective view of a shaft coupling; FIG. 2 is a lower back perspective view thereof; FIG. 3 is a front view thereof; FIG. 4 is a back view thereof; FIG. 5 is a left side view thereof; FIG. 6 is a right side view thereof; FIG. 7 is a top view thereof; FIG. 8 is a bottom view thereof; FIG. 9 is a schematic cross-sectional view thereof taken along line 9-9 in FIG. 3; FIG. 10 is a schematic cross-sectional view thereof taken along line 10-10 in FIG. 3; FIG. 11 is a schematic cross-sectional view thereof taken along line 11-11 in FIG. 3; FIG. 12 is a schematic cross-sectional view thereof taken along line 12-12 in FIG. 7; and, FIG. 13 is an upper front perspective view showing the shaft coupling in a state of use in which two shafts connected by the shaft coupling are shown by broken line for illustrative purpose only and form no part of the claimed design.
